CLAIM

The ornamental design for a notebook computer as shown
and described.

DESCRIPTION

FIG. 1 is a perspective view of a notebook computer
showing our new design in an opened state;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a perspective view thereof showing the notebook
computer of FIGS. 1-8 in a closed state; and,
FIG. 10 is another perspective view thereof showing the
notebook computer of FIGS. 1-8 in a closed state.
The even-dashed broken lines shown in the drawings illus-
trate portions of the notebook computer that form no part of
the claimed design. The dot-dashed broken lines represent
boundaries of the claimed design and form no part thereof.
